TYPEWRITING MACHINE

William A. Gabrielson, Syracuse, N. Y., assignor
to L. C. Smith & Corona Typewriters, Inc.,
Syracuse, N. Y., a corporation of New York

Application June 24, 1940, Serial No. 341,995

7 Claims. (Cl. 197—179)

The invention relates to improvements in typewriting machines and more particularly to the tabulating mechanism of such machines.

The principal object of the invention is to provide for a typewriting machine an improved tabulating mechanism of the key-set type which is of simple and inexpensive construction.

Other objects are to provide in a key-set tabulating mechanism settable column stops of simplified and improved construction, to provide an improved mounting for said stops, and an improved assembly of the settable stops and a stop carrying bar.

A further object of the invention is to improve and simplify the key set tabulating mechanism disclosed in U. S. Patent No. 2,099,011, issued November 16, 1937, to Carl Gabrielson et al.

To the foregoing and other ends which will hereinafter appear, the invention consists of the improved devices, features of construction, and arrangements and combinations of parts and devices hereinafter particularly described and particularly pointed out in the appended claims.

In the accompanying drawing illustrating the preferred embodiment of the invention:

Fig. 1 is a fragmentary vertical longitudinal sectional view of the improved machine taken on the line 1—1 of Fig. 2;

Fig. 2 is a fragmentary transverse sectional view of the machine taken approximately on the line 2—2 of Fig. 1, certain parts being broken away for clarity of illustration of the stop setting means;

Fig. 3 is a detail sectional view taken approximately on the line 3—3 of Fig. 1;

Figs. 4 and 5 are detail views illustrating, respectively, the setting of a column stop individually in operative position, and the setting of a column stop individually in inoperative or cleared position;

Fig. 6 is a detail view showing, in end elevation, part of the right hand end of the platen carriage; and

Fig. 7 is a detail transverse sectional view of the column stop bar and pivot wire on an enlarged scale.

The invention has been shown embodied in an L. C. Smith typewriting machine having a tabulating mechanism constructed as shown in the patent above referred to except as said mechanism is modified by the present improvements. Only so much of the known machine as is necessary for a clear understanding of the present invention has been shown and will be described.

The platen carriage 10 of the machine has the

usual roller platen 11 journaled therein and is mounted as usual on the main framework 12 of the machine to travel back and forth transversely of the machine and is letter spaced from right to left under control of the usual carriage escapement mechanism (not shown). The carriage 10 is releasable from control of the carriage escapement mechanism by the usual escapement releasing or carriage releasing mechanism (not shown) for tabulating jump or running movement of the carriage from right to left. Fixedly held to the carriage adjacent opposite ends of the carriage are two brackets 13 which rigidly support the opposite ends of a column stop carrying bar 14 which extends horizontally transversely of the machine, said stop bar being fixedly held at each of its ends to the adjacent bracket 13 by a screw 15.

The parts heretofore described are constructed as described in the prior patent above mentioned. The improvements made by the present invention in the tabulating mechanism of the machine of said prior patent will now be described.

The column stop carrying bar 14 is of oblong cross-section and is held to the brackets 13 with its two wider faces disposed in superposed horizontal planes. This bar is slotted inward from top to bottom thereof along both its front and rear edges at letter space intervals to provide a row of column stop guiding and spacing slots 16 along the front edge of the bar and a row of column stop guiding and spacing slots 17 along the rear edge of the bar. Each slot 16 is directly opposite a different one of the slots 17 and the slots of each row are spaced a letter space apart, there being one slot 16 and an opposed slot 17 for each letter space position of the platen carriage.

Settable column stops 18 of novel construction, one for each letter space position of the carriage, are rockably mounted on the stop bar 14, certain of the stops 18 being omitted from the drawings for clarity of illustration. These novel stops have also a novel mounting on the bar and a novel coaction with the bar to maintain their mounting thereon and to arrest and detain each stop in either of two positions relatively to the bar, one position being the operative or set position of the stop and the other being the inoperative unset or cleared position of the stop.

The improved stops are pivotally held to a straight pivot wire 19 which in the improved construction is insertible in and removable from a groove 20 which extends longitudinally of the stop bar 14 and is formed in the front vertical edge face of the bar. In the improved stop bar

the groove 20 surrounds not more than half the circumference of the pivot wire and preferably (as shown) less than half of the circumference of the wire, so that the wire may be moved transversely of the wire or fore-and-aft of the machine bodily for disengaging the wire from and engaging it in the groove. Ready engagement of the pivot wire with the bar and disengagement of the wire from the bar is thus provided for and also the expense of cutting an undercut wire-holding groove of key-hole cross-section is avoided. The depth of groove 20 transversely of the bar 14 is substantially less than that of slots 16.

The improved stops are adapted to hold the pivot wire in the groove 20 as hereinafter explained, and each of the improved stops consists of a single piece of sheet metal. The stops are so formed as to be readily stamped in quantity by inexpensive dies from a sheet of metal which is slightly resilient or springy, and each stop is so formed as to be slightly resilient or springy edgewise of the stop. The improved stops are adapted as hereinafter described to hold themselves and the pivot wire 19 assembled with the stop bar for setting and unsetting of the stops and to prevent accidental disconnection of any stop and of the pivot wire from the bar, while permitting ready assembly of the wire and stops with the bar and disassembly of the stops and wire from the bar. The improved springy one-piece sheet metal stops include integral parts thereof which are coactive with the stop bar as hereinafter explained to arrest pivotal movement of each stop in a set or operative position and in an un-set or inoperative "cleared" position as well as to prevent accidental disassembly of the stops and pivot wire from the bar. The improved stops also are formed with integral means coactive with a universal stop unsetting or clearing device and with integral means coactive with a device for individually setting and unsetting the stops, which devices may be, and preferably are, identical with the devices for said purposes provided in the machine of the prior patent above referred to. The improved stops are also provided with integral means coactive when the stops are set with a suitable stop on the machine frame, which frame carried stop may be, and preferably is, identical with the frame stop of the machine of said prior patent and is similarly controlled.

Each of the improved one-piece sheet metal stops 18 is constructed as follows in the preferred embodiment shown in the drawings. Each stop consists of a substantially straight arm having at one end a cylindrical pivot aperture through which the pivot wire 19 extends, and of an arcuate arm or sector arm integral with the straight arm and extending from the other end of said straight arm through an arc of slightly more than 90 degrees, the center of which arc is substantially coincident with the center of the pivot aperture in the straight arm of the stop. When the stops are assembled on the stop bar the straight arm of each stop extends upwardly in the construction shown and the arcuate arm of each stop curves downwardly and rearwardly. At its outer edge the arcuate arm of each stop 18 is formed with three outwardly extending integral teeth or projections or lugs 21, 22 and 23 projecting from said arm edge substantially radially of the pivotal axis of the stop. At its inner edge the arcuate arm of each stop 18 is formed with two integral inwardly extending

projections or lugs 24 and 25 spaced apart a substantially greater distance than the vertical thickness of stop bar 14 and engageable respectively with the upper and lower faces of the solid

5 unslotted medial portion of the stop bar to limit the extent of the pivotal setting and unsetting movements of the stop. Projections 25 of the stops 18 also cooperate with the stop bar to prevent accidental disconnection of the stops and 10 wire 19 from the bar 14. At its inner edge the arcuate arm of each stop 18 is formed with an inwardly extending stop latching projection or lug 28 located intermediate the projections 24 and 25 and extending inward a lesser distance than projections 24 and 25. The projection 28 is 15 a cam projection or hump having a rounded or arcuate edge for engagement with the stop bar 14 as hereinafter more fully described.

When a stop 18 is rocked about its pivot wire 20 19 from its inactive unset or cleared position of Figs. 1, 2, 3, 5 and 6, to its active or set position of Fig. 4, the projection 24 abuts the top face of stop bar 14 to arrest the stop in set position, and hump or projection 28 is yieldingly forced down 25 past the upper corner or edge of the bar at the inner end or root of the slot 17 and, when the stop is arrested by projection 24, said hump presses resiliently against the inner vertical surface of bar 14 at the root of the slot to releasably hold or latch the stop against accidental movement from set position. When a stop 18 is rocked about its pivot wire 19 from set position to unset or cleared position, the projection 25 abuts the under face of the stop bar to arrest 30 the stop in unset position, and hump or projection 28 overhangs the upper face of the bar 14 and yielding presses thereagainst at the upper end of the root of slot 17 to releasably latch or hold the stop in unset or cleared position.

40 Each stop 18 is inherently resiliently springy or bendable edgewise of the stop or fore-and-aft of the machine to permit of the aforesaid self-latching operations and also to permit assembly and disassembly of the stops and their pivot wire 45 from the bar. The resilience of the stop may be enhanced by making the straight arm thereof quite narrow in the plane of the stop, i. e. fore-and-aft of the machine, as shown. Each stop is guided to swing about the pivot wire 19 in a vertical plane extending fore-and-aft of the machine, each stop being so guided by a pair of slots 16—17 the side walls of which firmly hold the stop against sidewise movement transversely of the machine. By pushing rearwardly on the 50 projections 25 of the set of stops 18 to slightly resiliently expand the stops edgewise and then swinging the stops about the pivot wire 19 until the lower ends of the arcuate arms of the stops are moved upward clear of the stop bar 14, the 55 entire set of stops 18 and the pivot wire 19 will become disengaged as a unit from the stop bar.

All of the stops 18 which are in set position at any one time may be simultaneously unset or restored to inactive cleared position by a universal stop restoring or unsetting means provided on the platen carriage. The means shown in the drawing for this purpose is the same as that disclosed in the prior patent above mentioned, and need be only briefly described. A 60 rock shaft 31 journaled in brackets 13 on the carriage extends horizontally across the machine above the bar 14 and the set of stops 18 and has fixed thereto a pendent rigid fin or blade 32 which extends down between the projections 21 and 22 of all stops 18. A spring 33, coiled about

shaft 31 and engaged with fin 32 and with a projection 34 on one bracket 13, normally urges the fin rearward to and holds it in the position shown in the drawing. On the right hand end of shaft 31 is fixed a sector gear 35 the teeth of which mesh with those of the sector gear arm of a two-arm key lever 36 the other arm of which lever is formed with a key 37. Key lever 36 is pivoted to the adjacent carriage bracket 13 at 38 to rock up and down and is provided with a stop 39 normally engaged over a stop 40 on said bracket, as shown in Fig. 6. Upon depression of key 37 the fin 32 will swing forward and unset all set stops by pressure of the fin on projections 21 of said set stops, and upon release of said key said fin will return to normal position.

Projections 21 and 22 of each stop are spaced apart along the arcuate arm of the stop to permit the stop to be swung from unset to set position or vice-versa with the fin in normal position without collision of said projections with the fin when the latter is in normal position. The stops may thus be individually set and unset by the individual stop-setting and unsetting means disclosed in the prior patent and shown in part in the drawing illustrating the present invention. So much of said means as is necessary to an understanding of the present invention is shown and will be briefly described.

Said last-mentioned means comprises the stop-setter and unsetter 41-43 rockable by key-applied force either to the position shown in Fig. 4 or to the position shown in Fig. 5 from the normal idle intermediate position of said setter and unsetter shown in Figs. 1, 2 and 3 and automatically returned to said last-mentioned position from either of the first two mentioned positions upon release of the key-applied force. The setter and unsetter comprises a yoke 41 having its two legs pivoted at their rear ends on a fixed pin 42, one leg of said yoke being formed with a stop setting and unsetting finger 43. Pin 42 extends horizontally transversely of the machine and is fixed in the main frame 12 of the machine above and behind the stop bar 14.

The key-controlled means for so shifting the stop setter and unsetter from and restoring it to idle position includes a vertically reciprocable link 45 connected at 44 to the right hand leg of yoke 41, and a vertically reciprocable link 53 connected to link 45 by a cross-pin or cross-rod 54 rigid with both links. Shifting of the link device 45-53-54 upward by key-applied force from a normal position thereof to which it is automatically restored upon release of key force rocks the stop setter and unsetter from normal position to that of Fig. 5 to unset a single set stop 18 aligned with the finger 43, the finger thrusting against projection 22 of said stop to unset the stop. Shifting of the link device downward by key-applied force from its normal idle position to which it is restored upon release of the applied key force rocks the stop setter and unsetter from normal idle position to that of Fig. 4 to set a single stop 18 aligned with finger 43, the finger thrusting against projection 23 of the stop to set the stop. Restoration of the rigid link device 45-53-54 to normal position restores the stop setter and unsetter to normal position.

The finger 43 of the device 41-43, which swings the stops individually about their pivotal axis to set or unset a single selected stop at a time, extends forwardly from the yoke 41 and is located substantially in the medial vertical longitudinal plane of the machine. The thick-

ness of finger 43 transversely of the machine is substantially equal to that of each column stop 18 and in each letter space position of travel of the carriage a different one of the stops 18 is located in the same vertical fore-and-aft plane through the machine in which the finger 43 lies. The finger projects in between the projections 22 and 23 of any stop 18 aligned therewith. The spacing apart of the two projections 22 and 23 of each stop is such that during travel of the carriage, while the stop setter and unsetter is in idle or neutral position, the projections 22 of all stops 18 will pass above the finger 43 and the projections 23 of all stops 18 will pass below finger 43 whether the stops be set or unset. The spacing apart of the projections 22 and 23 of each stop 18 is also such that, when said stop is registered with finger 43, downward swinging of the finger from idle position will set that stop by thrust of the finger on projection 23 and upward swinging of the finger from idle position will unset the stop by thrust of the finger against projection 22, but return movement of the finger to idle position will not shift the stop.

The projections 23 of the column stops 18 also serve as abutment elements of said stops for coaction with a suitable settable counter stop 86 on the machine frame in tabulating operations. The counter stop shown and the means for setting it correspond to those disclosed in the prior patent above-mentioned. This counter stop 86 is located substantially midway the sides of the machine and is guided at its upper end adjacent the stop bar 14 in a fore-and-aft extending slot 87 in a part of the main frame 12. Suitable key-controlled means as set out in said prior patent are provided for releasing the carriage for a tabulating jump from right to left and shifting the counter stop from a normal idle position of said stop shown in Figs. 1, 2 and 5 to an active position shown in Fig. 4.

When counter stop 86 is in idle position stops 18 will freely pass it. When counter stop 86 is in active position all unset ones of the stops 18 will pass it but no set stop will pass it. The projections 23 of set stops will collide sidewise with the active counter stop in successive tabulating jumps or runs of the carriage. The projection 23 of each set stop is substantially directly behind and close to the stop bar so that it will be firmly supported laterally by the side walls of slot 87 in which the set stop is engaged.

What I claim is:

1. A typewriting machine having a tabulating mechanism comprising a column stop carrying bar provided with a longitudinal groove, a pivot wire for a series of column stops, and a series of column stops engaged with said wire for setting and unsetting rocking movements about said wire and releasably engaged with the bar to releasably hold said wire and stops in assembled relation with the bar, said wire being movable laterally therefrom into and out of said groove and releasably retained in the groove by the engagement of the series of stops with the bar and wire, said stops being resiliently expandable to free the stops and wire from the bar.

2. In a typewriting machine, the combination of a column stop bar provided at each of two opposite edges thereof with a row of inwardly extending slots, a set of resiliently expandable one-piece column stops, each stop having portions engaged in one slot of each row of slots, and a pivot wire for the set of stops extending across all the slots of one of said rows of slots, said

bar having in that edge thereof provided with said last-mentioned row of slots a longitudinally extending groove into and out of which said pivot wire is movable by lateral shifting of the wire relatively to the bar, each of the stops having a pivotal engagement with the wire and a shiftable and releasable engagement with the bar adjacent the opposite slotted edge of the bar by which the stops and wire are releasably held to the bar and the stops may be rocked about the pivot wire for setting and unsetting the stops, said stops being resiliently expansible to free the stops and wire from the bar.

3. In a typewriting or like machine, a tabulating mechanism comprising a column stop bar, an edgewise resilient one-piece rockable column stop having opposite ends separated to straddle the bar, and a stop pivot with which said stop is engaged at one of said ends for rocking of the stop relatively to the bar, said bar having an open seat for said pivot in which said pivot is releasably held by the stop, the stop adjacent its other end resiliently bearing edgewise of the stop against the bar, said stop bar having a slot in which the said other end of the stop is engaged, and said stop having projections engageable with the bar to limit rocking of the stop in opposite directions relatively to the bar to set and unset the stop, said stop being resiliently expansible edgewise to release the stop and its pivot from the bar.

4. In a typewriting or like machine, the combination of a main frame, a platen carriage mounted on the main frame to travel transversely of the machine, a column stop bar mounted on the carriage and extending transversely of the machine, said bar having along each of two opposite edges thereof a row of slots extending inwardly transversely of the bar, said bar having a channel in one of said edges intersecting the slots in said edge, a set of one-piece sheet metal column stops straddling said bar, and a pivot wire for said stops removably seated in said channel and intersecting the slots in the channeled edge of the bar, one end of each column stop being pivotally engaged with said wire and engaged in a slot of the adjacent row of slots, the other end of each stop passing through a slot of the other row of slots, each stop being provided with a pair of spaced apart integral projections adjacent said other end engageable with opposite faces of the bar to limit setting and unsetting rocking movements of the stop about the pivot wire and with an integral cam hump intermediate said projections coercive with the bar to releasably latch the stop in either set or unset position, each of said stops being open between its opposite ends and resiliently springy to permit spreading of its ends apart in assembling the stop in straddled relation with the bar and to release the stops and the pivot wire from the bar, and each stop normally resiliently pressing in substantially opposite directions against the pivot wire and against the bar.

5. In a key set tabulating mechanism, a rockably settable and unsettable column stop formed

of a single piece of sheet metal inherently springy and resiliently expansible, said stop having spaced apart ends one of which is formed with a pivot bearing to engage a pivot wire for a set of such stops, said stop being shaped between its ends to straddle a column stop bar and being resiliently expansible between its ends for attachment to and detachment from the column stop bar, and resiliently contractible to exert substantially opposed pressures on its pivot wire and the bar while assembled on the bar in bar straddling position, said stop having integral projections for coaction with stop setting and unsetting means, one of which projections also constitutes

an abutment for coaction with a counter stop, and said stop also having a pair of integral projections for engagement with said bar to limit rocking setting and unsetting movements of the stop relatively to the bar.

6. In a key set tabulating mechanism, a one-piece sheet metal column stop rockably settable and unsettable consisting of a straight arm and an arcuate arm extending from one end of the straight arm, the other end of the straight arm being formed with a pivot bearing for engagement with a pivot wire, the arcuate arm being curved substantially about the said pivot bearing as a center and the stop being inherently resilient for separating and approaching movements between the pivot bearing end of the straight arm and the free end of the arcuate arm, the arcuate arm having outwardly extending projections at its outer edge for engagement by stop setting and unsetting means and having at its inner edge projections for engagement with a stop carrying bar to limit setting and unsetting rocking movements of the stop about the pivotal axis of the stop, and an integral bearing part adapted to engage the stop carrying bar to releasably hold the stop in set or unset position, said bearing part being on the inner edge of the arcuate arm between the two projections adapted to engage the stop carrying bar.

7. A typewriting machine having a tabulating mechanism of the key-set type including a set of column stops, one stop for each letter space position of the carriage and each stop rockably mounted on a stop-carrying bar for movement from set to unset position, wherein each column stop is formed of a single piece of sheet metal, and has an arm provided at one end with a pivot bearing, and an arcuate arm for engagement with a counter stop and extending from the other end of the pivot-bearing arm in an arc substantially concentric with the pivot bearing of the stop, the said two arms of each stop being otherwise disconnected and adapted to straddle the stop-carrying bar, and the stop being inherently edgewise resiliently expansible and contractible between its ends for attachment to and detachment from the stop-carrying bar and to exert substantially opposed pressures on its pivot at one end and on the said stop-carrying bar at its other end when assembled on the stop-carrying bar.

WILLIAM A. GABRIELSON.
